UNITED STATES PATENT OFFICE

RAYMOND A. WINCHESTER, OF LIND, WASHINGTON

ROTARY VALVE

Application filed January 23, 1928. Serial No. 248,707.

My present invention relates to improvements in rotary valves for use in internal combustion engines. The primary object of the invention is the provision of a rotary valve device in the head of the engine by means of which the fuel is distributed to the cylinders of the engine and also by means of which the exhaust gases are transferred from the cylinders of the engine to the exhaust manifold. In carrying out my invention I provide a novel construction for the engine head and a novel construction for the rotary valve as will be hereinafter more fully pointed out and claimed.

In the accompanying drawings I have illustrated one complete example of the physical embodiment of my invention in connection with a four-cylinder internal combustion engine, but it will be understood that the number of cylinders may be varied and my invention is therefore adapted for use with types of engines other than the four-cylinder engine illustrated in the drawings.

The drawings show the parts combined and arranged according to the best mode I have so far devised for the practical application of the principles of the invention.

Figure 1 is a view in elevation showing a four-cylinder engine equipped with the valve mechanism of my invention.

Figure 2 is a top plan view of the parts in Figure 1.

Figure 3 is a longitudinal vertical sectional view at line 3—3 of Figure 2.

Figure 4 is an enlarged transverse vertical sectional view at line 4—4 of Figure 3 showing the exhaust open.

Figure 5 is a transverse vertical sectional view at line 5—5 of Figure 3 showing one of the intakes open.

Figure 6 is a transverse vertical sectional view at line 6—6 of Figure 3 showing one of the exhaust ports closed.

Figure 7 is a sectional detail view at line 7—7 of Figure 3 showing one of the intake ports closed.

Figure 8 is an enlarged detail sectional view at the central portion of the cylinder head showing the intermediate parts of the rotary valve and connections.

In order that the general assembly and relation of parts may readily be understood I have illustrated a four-cylinder engine of usual type in which the cylinders are designated as 1, 2, 3 and 4 and these cylinders are fired in any usual order. The pistons are designated 5 and the crank case 6 of the motor has the usual crank shaft 7 from which the drive chain 8 for the valve is operated and this chain operates a valve wheel 9 for rotating the valve in the top or head of the engine.

A usual type of carburetor 10 is employed for furnishing the fuel through the intake manifold which comprises branches 11 to cylinders 1 and 12 to cylinder 4 and the intermediate branch 13 to the two intermediate cylinders 2 and 3.

The exhaust pipe 14 has a branch 15 for receiving the gases of combustion from the cylinders 1 and 2 and a branch 16 receives the gases of combustion from cylinders 3 and 4.

The head of the engine or motor is conveniently made up in sections comprising the two cylindrical end sections 17 and 18 and an intermediate section 19, the parts being bolted together and provided with the usual water-jacket 20 for cooling the motor head.

In Figure 3 two exhaust outlets 21 and 22 are shown in the sections 17 and 18, respectively.

The rotary valve is supported to rotate within the sectional head and it comprises two rigidly joined sections so that the valve may readily be assembled or dismantled with facility when necessary, and the intake manifold is designed to supply the fuel directly to the two end cylinders and to the two intermediate cylinders in order that the fuel gas will have a minimum distance to travel to the respective cylinders.

Within the central section 18 a walled structure 23 is provided to form a distributing chamber 24 for the fuel gas, and the cylinder head is provided with inlet ports 25, 26, 27 and 28 to the respective cylinders 1, 2, 3 and 4. These cylinders are also provided with exhaust ports 29, 30, 31 and 32 located in the engine head and passing through the valve casing 33. This valve casing is cylin-

drical in shape and is fashioned within the sections 17 and 19 of the engine head to receive the rotary valve. The rotary valve is made up principally, as seen in Figure 8, of two cylindrical sections 34 and 35 and within these sections are provided a pair of alined sections 36 and 37 of reduced diameter and jointed within the chamber 24 by a rigid joint 38. Packing rings 39 are provided for these sections 36 and 37 within the distributing chamber 24 and ball bearings 40 are provided in the sections 17 and 19 of the engine head for the complementary annular grooves 41 in the exterior faces of the valve sections 34 and 35. At their outer ends these valve sections 34 and 35 are closed by means of end plates 42 of the engine head and the inner cylindrical sections 36 and 37 project outwardly through and beyond these end plates 42 of the engine head to form trunnions upon which the rotary valve is journaled. The wheel 9 is rigidly fixed to one of these trunnions and the valve is turned through the drive chain 8 and connections to this wheel. Packed joints 43 are provided for the trunnions and braces 44 are provided for the intake manifold branches supplying gas to the ends of these trunnions. All of the radial inlet ports of the rotary valve are designated 45 and all of the radial exhaust ports of the rotary valve are designated 46, and of course the inlet ports and exhaust ports in the valve are arranged in predetermined positions with relation to the complementary ports in the valve casing in order that the engine may operate with explosions in its cylinders in regular predetermined order.

The usual accessories are provided for cooling the engine head and packing the operating parts, and other necessary accessories are of course used although not herein referred to.

By means of the chain drive the rotary valve is turned continuously while the engine is operated and the fuel charges are supplied to the respective cylinders in regular order. The exhaust gases from the several cylinders are conveyed therefrom through the rotating valve and the engine operates with a smoothness and uniformity that insures efficiency with a minimum of consumption of fuel gas.

Having thus fully described my invention what I claim as new and desire to secure by Letters Patent is:

1. The combination with a valve casing of a pair of spaced cylindrical sections forming a rotary valve, a central inner fuel tube within each section having projecting ends and provided with a separate exhaust passage therethrough, there being exhaust ports for co-action with said passage, a rigid joint between adjoining ends of said tubes, means for supplying fuel to the outer ends of said tubes,

and means for supplying fuel to the joined ends of said tubes.

2. The combination with a sectional engine head comprising a pair of spaced cylindrical valve casings and an intermediate gas chamber, said sections having exhaust ports therein, of a pair of spaced cylindrical valve sections, an inner central tube for each valve section having exhaust passages and its ends projecting beyond the ends of the valve sections, a rigid joint between the adjoining inner ends of said tubes, means for supplying fuel gas to said adjoining ends, means for supplying fuel gas to the outer ends of said tubes; means for supplying fuel charges from said tubes to the respective cylinders, and means for exhausting gases of combustion through said exhaust passages in said central tubes.

3. An engine head comprising a pair of outer sections and an inner section rigidly joined together, said inner section forming spaced cylindrical valve casings, a rotary valve comprising two spaced, enlarged, cylindrical sections in said spaced casings, a central fuel tube having a separate exhaust passage therethrough and located within each valve section, there being exhaust ports for co-action with said passage, means forming a rigid joint between said tubes, and intake ports as described.

In testimony whereof I affix my signature.

RAYMOND A. WINCHESTER.
